DOUBLE CONTAINER

Abraham N. Spanel, Princeton, N.J., assignor to International Latex Corporation, Dover, Del., a corporation of Delaware

Filed Feb. 14, 1961, Ser. No. 89,256

5 Claims. (Cl. 206—47)

This invention relates to double containers in which a smaller inner container is adapted to be burst without bursting the larger outer container, so that when desired the contents of the inner container may be mixed with the contents of the intact outer container.

One instance of a product of this type, in which the article should be softly flexible to fit the human face or various contours to which it may be applied, is the refrigerating package shown in Patent No. 2,925,719 to Robbins et al. It has an inner sealed envelope filled with water. An outer sealed envelope contains both the inner envelope and a water-soluble chemical which has an endothermic heat of solution. The envelopes are flexible plastic and when the package is squeezed the inner envelope breaks and the water contacts the chemical. The heat of solution is absorbed and the package becomes a cold pack.

These refrigerating packages are often to be used under emergency conditions, for example to hold down swelling due to injury, wherein the user may not be familiar with the design and functioning of the product and may be hurried or even distraught. If the product is so designed that when it is squeezed the inner container will rupture locally, with a limited break in just one part of the inner envelope, then only a limited quantity of the water from the inner container may come into contact with the chemical and the rest may remain inside the inner container. This leaves appreciable quantities of the salt undissolved, and only a part of the cooling capacity of the package is realized. Under likely conditions of application the user may neither sense this deficiency nor take the time to resort to such kneading or turning as might serve to discharge all the water from the inner container.

The present invention assures that when the inner container is broken at all it will split wide open and let out all the water to produce maximum coldness.

I attain this result by making the outer envelope of stretchable plastic film and the inner envelope of non-stretchable plastic film having the combination of a moderately high bursting strength and a very low tear strength, that is, a high tear propagation characteristic. When such an envelope filled with water is squeezed to burst it, the relatively high pressure present at the moment of initial rupture will propagate an immediate tear that splits the envelope wide open. The reason that the tear propagation characteristic must be very high is that upon initial rupture some of the water or residual air escapes and drops the pressure almost instantaneously (unless the person squeezing the bag makes a rather extraordinary effort to press harder when the container begins to give). This, it is necessary for the purpose of this invention to make the inner container of material which will tear across an entire face of the envelope while the pressure is rapidly dropping to zero. While a higher burst strength would permit of a higher tear strength, the burst strength must in practice be well within the range of manual squeezing force, so the purpose of the invention can only be attained by combining with that moderately high bursting strength a very high tear propagation characteristic.

The drawings illustrate a package of the sort this invention is applicable to.

2

FIGURE 1 shows a double package 15, having inner envelope 10 filled or largely filled with water 12, and endothermic chemical 14 also contained in the outer envelope 16.

5 FIGURES 2 and 3 show for simplicity only the inner container.

FIGURE 2 illustrates an inner container made of relatively stretchable material having a low tear propagation characteristic so that when burst by application of pressure above its bursting strength only a slight break is created in the wall of the envelope and much of the water is held in the envelope when maintained in the position shown.

10 FIGURE 3 illustrates an inner envelope of the type used in the present invention which has a tear strength equal to or less than the bursting strength of the relatively non-stretchable plastic and a high tear propagation characteristic so that application of bursting pressure causes substantially complete splitting of the material 20 across at least one face of the envelope.

15 FIGURE 4 is a graphic representation of the co-ordinated burst strength and tear strength characteristics of the inner envelope of the double container of the invention.

25 In FIGURE 4, no exact values are assigned to B_{min} which is the minimum acceptable burst strength of the material of the inner envelope, and B_{max} which is the maximum acceptable, for the reason that these may vary somewhat depending upon the size and shape of 30 the envelope. The acceptable range of values for a representative size and shape of envelope is about 30 p.s.i. to about 60 p.s.i. on the Mullen Burst Test, which reads in pounds per square inch. No novelty is claimed in these burst strength values by themselves, the novelty 35 lying in the combination of this general range of moderately high burst strength together with a corresponding very low tear strength and a correspondingly high tear propagation characteristic.

40 I have found that materials with burst strengths all in the range of 30 to 60 p.s.i. have tear strengths which differ widely, some being a hundred times as resistant to tear as others with the same burst strength. This is with a test procedure wherein a portion of the top edge of a sample strip of sheet plastic material is 45 clamped to hold it, a clamp is attached next to that portion, with a weight suspended from it, and a standard short slit is cut in the top edge between the two clamps. The weight necessary to cause the sample to tear apart as a continuation of the slit is recorded as the tear strength. 50 In the test equipment used, the free clamp weighed 8 grams, so values below 8 grams were not distinguishable. Values were recorded from as high 800 grams down to 8 grams (or lower).

55 The fundamental concept of the invention is the selection and use of a material having the requisite moderately high burst strength and at the same time a corresponding very low tear strength for the inner envelope, while the outer envelope is resistant to rupture when hand manipulated to produce the required pressure to burst the inner envelope. The outer envelope is desirably made of an elastomer-like material, which among others may be polyethylene or vinyl-type resins. The boundaries may be identified empirically as a burst strength (in relation to the size and shape of the filled inner envelope) high 60 enough not to burst in shipping and handling and low enough to be manually burstable, and a tear strength 65 low enough so that an initial rupture will propagate the tear to split the envelope wide open during the almost instantaneous period when the pressure is dropping from bursting pressure to zero. In terms of scale values they may be identified as any satisfactory burst strength in- 70

cluding and lying in the general vicinity of 30 to 60 p.s.i., and a tear strength (after initiation of rupture) of not more than about the same value in grams, to wit a maximum of not more than about 60 grams, ranging down toward zero. The higher the burst strength, the higher the tear strength may be. The upper limit of the tear strength in grams has the same numerical value as the selected burst strength, in pounds per square inch.

This combination is found in cellophane about 1.5 mils in thickness, its burst strength being 50 to 60 p.s.i. and its tear strength being well within that upper limit, namely, 8 grams or less. When greater waterproof quality is desired, an inner layer of suitable highly waterproof plastic film may be laminated to the cellophane, as indicated at 10a and 10b in FIGURE 3. The inner layer may be of material which, if thicker and used as the only layer, would have too high a tear strength, provided the outer layer is unstretchable and the composite material is kept within the combination of characteristics set forth above.

The result is a product which serves the intended purpose effectively and by its very constituency guards against the partial ineffectiveness which with other constituencies can often in large measure defeat the intended purpose of the product.

Having described the nature of my invention and indicated how it can be practiced,

I claim:

1. Container comprising an outer larger pliable envelope of one bursting strength containing a water soluble chemical having an endothermic heat of solution and an inner smaller water-filled pliable envelope of bursting strength less than that of the outer envelope, the inner envelope being made of plastic film having a Mullen burst strength of about 30 to 60 p.s.i. and having a tear strength in grams measured as herein described, the upper limit of tear strength in grams having the same numerical value as the burst strength in p.s.i.

2. A container according to claim 1 in which the plastic film of the inner envelope is cellophane.

3. In a double envelope package having an inner sealed envelope substantially filled with liquid, an outer sealed envelope containing the inner envelope and a substance adapted to be mixed with said liquid upon bursting of the inner envelope upon application of force to the outer envelope, said outer envelope having a higher bursting strength than said inner envelope, the improvement comprising said inner envelope constructed of sheet plastic having a tear strength, the upper limit of which expressed in grams has the same numerical value as the burst strength expressed in p.s.i., such that the envelope splits open at least on one face thereof upon application of bursting pressure thereto whereby to substantially instantly completely discharge the liquid from the inner envelope upon subjecting the same to bursting pressure.

4. A device as claimed in claim 3, in which the inner envelope is made at least in part of substantially unstretchable sheet plastic.

5. A device as claimed in claim 3 in which the inner envelope is a two-ply laminate of plastic material, the inner ply being of highly waterproof plastic and the outer ply being of less waterproof but substantially unstretchable plastic.
